UNITED STATES PATENT OFFICE.

ROBERT REACH, OF PHILADELPHIA, PENNSYLVANIA.

BASE-BALL MASK.

SPECIFICATION forming part of Letters Patent No. 364,543, dated June 7, 1887.

Application filed March 2, 1887. Serial No. 229,438. (No model.)

To all whom it may concern:

Be it known that I, ROBERT REACH, a citizen of the United States of America, residing at Philadelphia, in the county of Philadelphia 5 and State of Pennsylvania, have invented certain new and useful Improvements in Base-Ball Masks, of which the following is a specification, reference being had therein to the accompanying drawings.

This invention has relation to improvements in masks for base-ball players; and it consists in the combination and arrangement of the parts, substantially as hereinafter fully set forth, and pointed out in the claims.

In the accompanying drawings, Figure 1 is a front view of my improved mask for base-ball players. Fig. 2 is a vertical or longitudinal section thereof. Fig. 3 is a rear view of the same. Fig. 4 is a detail perspective of a 20 section of the inflated pad; and Fig. 5 is a front elevation of a modification.

In the embodiment of my invention I construct or make the mask A, which is adapted to be worn on the face of the ball-player, of a series of curved horizontal wires or members, a' a'' a'' a'' a'', the wires or members a, a'', a'', and a'' being connected at their ends to the innermost wire of an oval side frame, a''. This innermost wire of the oval side frame is jointed 30 by overlapping its looped ends, as shown, and is provided with the approximate contour or outline of the face from the chin upward, being placed next to the face when the mask is worn. This oval side frame is composed of two rigid stout wire supplementary frames or wings, C C, the purpose of which will appear further on. To either side of the mask, near the upper and lower horizontal portions of the oval side frame, are connected the ends of a longitudinal wire or member, b, which ends are bent at right angles to the vertical or main portion of said wire before passing and securing their looped ends around the oval side frame, a''. To these longitudinal wires or members 40 b are connected or secured the looped ends of the intermediate horizontal wires, a' a'', which are also caused to interlock or are secured to additional wires, an opening or space, B, being left between the wires or members a' a'', to give adequate viewing range for the player.

To the extreme outer curved portion of the

horizontal wire or member a'' is connected the upper forward looped end of a central bracing wire, b', which is clasped, as shown in Fig. 1, by the wires or members a' a'', and secured at its lower end to the lower horizontal portion of the oval side frame, a''. To the upper horizontal portion of this oval side frame is connected the upper rear end of an inclined strengthening or supporting wire or member, 55 C', which is bent and curved through a loop of the horizontal wire a'', and passed upwardly and bent through a loop formed in the wire or member a', whereby said wires are greatly strengthened at their outer curved portion, so 60 as to resist any inward pressure caused by a ball striking against the mask.

D is an approximately-oval rubber air-chamber or cushion, which in practice is inclosed within a strong leather jacket, d, which jacket 70 has projecting pieces or side extensions, d', apertured throughout their entire length, the purpose of which will soon appear. After placing the air-chamber D within the leather jacket d the same is securely held by stitching 75 through the projecting pieces or side extensions, d', an opening or space, however, being left at the lower or chin end of said jacket, the purpose of which will now appear.

At the lower end of the air-chamber D is 80 formed a small tube, d'', the outer half of which has a second tube, d', fitted thereon, the inner end thereof being designed to fit over and inclose a hole or aperture formed in the tube d'', the purpose of which will appear hereinafter. 85 This air-chamber, together with its inclosing-jacket, is secured to the mask by means of a long continuous leather lacing, e, passed through eyelet-apertures of the extensions d' of said jacket, and thus secured, a smooth surface is presented on the rear side of the mask. The opening or space before referred to as being provided in the lower or chin end of the jacket is designed to permit the tube d'' to project therethrough, and when it is desired 90 to inflate the air-chamber prior to the employment of the mask in a game of ball, the inner end of the outer or second tube, d', is turned or forced back upon itself, and by blowing through the hole or aperture formed in the center of the tube d'', the air-chamber will be 95 filled with air, causing its expansion, together 100

with its inclosing jacket. After sufficient air has been secured in said air-chamber, the same will be retained therein by first catching with two fingers the tube d^2 at a point between its 5 inner end and the aperture formed therein, and then turning to its former place the inner end of the tube d^3 , which will by reason of its tight fitting over the aperture prevent any possible escape of air. These tubes are then 10 to bent into the open end of the jacket, which open end is closed by means of a short lacing, also passed through eyelet-openings in the extensions of the jacket, as shown.

E is an elastic or other strap, one end of 15 which is connected or looped to one side of the mask, while its other end is adapted to be buckled to the opposite side of said mask, and by means of this strap, which is passed around the head of the wearer, the mask is secured in 20 position.

One of the principal advantages of my invention consists in providing an inflated chamber, which forms a continuous surface for contact with the face of the wearer, and thereby 25 dispensing with all chin-rests and forehead-bands, which have proved insufficient to protect the wearer from the detrimental effect of jarring and concussion caused by the striking of a ball against the mask.

I do not restrict myself to the exact construction of the mask as above detailed, for, without departing from the spirit of my invention, the same may be constructed as shown in Fig. 5. In this form of my invention the 30 middle or intermediate ones of the curved transverse wires or members whose inner ends are fastened or looped around the side frame are indented or crimped, as at e, alternately in and out, as are also the two innermost 35 longitudinal wires or members, e' e', and these transverse and longitudinal wires or members alternately intersect or cross each other upon opposite sides at their indentations or crimp portions, whereby they are adapted 40 to interlock each other, bracing and giving additional strength to the mask, and to rest at their intermediate portions or surfaces as well as their points of intersection flush 45 with each other. This construction, it will be seen, forms a firm substantial net-work, which guards the face of the player or wearer from liability of being struck and seriously wounded thereat, and effectively resists the 50 force of the ball as against the indentation of the mask should the ball happen to strike it as the player is attempting to catch the ball; also, the two most salient or middle transverse wires or members, a a, those about centrally 55 of the face are disposed somewhat farther apart 60 than the others, are curved, the upper one upward and the lower one downward or away from each other, as at e'' e'', at each side of the mask, about opposite the eyes of the wearer, for the obvious reason to give adequate view-

ing range for the player. The intermediate 65 longitudinal wires or members extend, the lower ones from the lower middle transverse wire or member, (to which they are fastened or looped,) and are looped or fastened to the lower end transverse wire or member, as before stated, while the two upper ones of the 70 said intermediate wires or members are connected to the upper middle transverse wire or member, and extend to the upper end transverse wire or member of the mask, thus leaving an extended opening, e', upon and between each side of the middle longitudinal wire or member and the innermost longitudinal side wires or members to further aid the 75 range of vision. The middle longitudinal or bridge wire or member may only extend and be connected at its upper end to the transverse wire next to the upper end wire of the mask, as shown.

Having thus fully described my invention, 80 what I claim, and desire to secure by Letters Patent, is—

1. The mask for ball-players, composed of a series of longitudinal and horizontal wires with looped portions, the oval side frame, and 90 the air-cushion, inclosed within a leather jacket having apertured extensions through which a lacing is passed for securing the same to said frame, all arranged substantially as shown and described. 95

2. In a base-ball mask, the combination, with the series of wires or members, of the upper centrally-disposed inclined strengthening or supporting wire or member, secured at one end to the oval wire and bracing the upper horizontal wires or members at their outer curved portions, and the lower central bracing-wire, arranged substantially as shown and described. 100

3. In a base-ball mask, the inflated cushion 105 comprising the rubber air-chamber having the rubber tubes, the leather jacket inclosing said chamber, and the lacing securing the same to the mask, substantially as shown and described. 110

4. The combination, with the mask and the air-chamber, of the tube secured thereto having a central aperture and the outer tube fitted on said former tube and having one end covering said aperture, substantially as shown, 115 and for the purpose described.

5. In a base-ball mask, the combination, with the air-chamber, of the leather inclosing-jacket having apertured side extensions, and the lacing passed through said apertures, substantially as shown and described. 120

In testimony whereof I affix my signature in presence of two witnesses.

ROBERT REACH.
